UNITED STATES PATENT OFFICE.

EDWARD SAMUEL AND VICTOR ANGERER, OF PHILADELPHIA, PA., ASSIGNEES TO WILLIAM WHARTON, JR., & CO., (LIMITED,) OF SAME PLACE.

CABLE-GRIP.

SPECIFICATION forming part of Letters Patent No. 352,356, dated November 9, 1886.

Application filed February 26, 1886. Serial No. 193,304. (No model.)

To all whom it may concern:

Be it known that we, EDWARD SAMUEL, a citizen of the United States, and VICTOR ANGERER, a subject of the Emperor of Austria, and both residing in Philadelphia, Pennsylvania, have invented certain Improvements in Cable-Grips, of which the following is a specification.

Our invention consists of certain improvements in the construction of the devices for supporting the grip-frame and for operating the movable bar of said grip-frame, the object of our invention being to permit the ready application of the grip to or its removal from the supporting-frame on the car, and to provide simple and efficient grip-operating devices which will not be disturbed by changes in the position of the grip-bar.

In the accompanying drawings, Figure 1 is a side view of our improved gripping device, looking in the direction of arrow 1, Fig. 2. Fig. 2 is a transverse section on the line 1 2, Fig. 1. Fig. 3 is a side view looking in the direction of the arrow 2, Fig. 2, with the lower portion of the grip omitted. Fig. 4 is a section on the line 3 4, Fig. 3. Fig. 5 is a section on the line 5 6, Fig. 3; and Figs. 6, 7, 8, and 9 are detached perspective views of parts of the device.

30 A is the frame, having wings $a a$, at the outer ends of which are sockets a' , which are adapted to fit over pins $b b$, on transverse bars B , at the front and rear of the frame. This frame A carries the grip-bar, at the lower end of which is the grip D, the peculiar construction of the latter forming the subject of a separate application, filed by us February 15, 1886, Serial No. 191,981. Various other forms of grip may, however, be employed, if desired, our present invention relating solely to the means for supporting the grip-bar and operating the movable portion of the same.

40 The transverse bars B are adapted to bearings on longitudinal hangers C, Fig. 3, which are in the present instance hung to the axles of the car, thereby permitting free lateral movement of the bars B and frame A, and also any lateral twisting movement—such, for instance, as may be caused when the car is rounding the curve.

In bearings in the frame A is a shaft, H, having an operating-lever, I, and provided at its inner end with a cam, h , adapted to act on the vertically-movable operating-bar F of the grip, which is guided by the fixed plates E E 55 of the grip-bar.

The plates E E are attached to a plate, G, Fig. 8, which is securely riveted to the said plates, and also to a bar, J, the latter projecting at each end beyond the plate G, and serving to support the plate G on the frame A, as will be described hereinafter.

The plate G has a central opening, g , to permit the free movement of the cam h of the shaft H, and the frame A is also recessed at a^2 65 for the same purpose. The plate F has an opening, f , for the reception of the cam h , and in the upper portion of this opening f is secured a shoe, f' , which is acted upon by the cam and is held in place by a pin, f^2 , passing through both the shoe and the plate F, a lip of the shoe extending up on the outside of the plate G, and tending to prevent any lateral play of the upper portion of the plate F. (See Figs. 2 and 8.)

75 The frame A, Fig. 6, has shoulders $c c$ at each end of a recess, K, into which the grip-frame X is inserted, these shoulders $c c$ serving as supports for the projecting ends of the bar J. A rib, d , on the upper portion of the frame A, projects over the bar J, and thus serves to confine the frame X vertically to the frame A.

Secured to or formed on the frame A are two keepers, $e e$, having their inner edges, e' , beveled, as best observed in Figs. 2 and 6, and when the frame X is in position in the frame A, a wedge, M, is inserted between the face of the plate G of said frame and the keepers $e e$ of the frame A, the outer faces, $m m$, of the wedge bearing against the inner faces, e' , of the keepers, and the inner faces, m' , of the wedge bearing against the plate G, so that any jarring of the frame A will tend to tighten the edge M and firmly retain the frame X in 90 place. The wedge is recessed at m^2 , to permit the free movement of the cam h and shoe f' . On the inner face of the wedge M are two hooked lugs, $n n$, which project beneath the ends $j j$ of the bar J, which have recesses j' at 100

the rear, as shown in Fig. 9, and the frame A is also recessed at *i*, to receive the lugs *n n*.

The wedge M is provided with a handle, N, preferably of the shape shown in Fig. 7, in order to facilitate the lifting of the wedge to release the frame X from the frame A, and as the wedge is raised the lugs *n* will engage with the projections *j*, so that the frame X can be readily removed with said wedge from the frame A, the handle being within easy reach through the trap in the car floor, and the frame X on the lifting of the wedge having sufficient lateral freedom to permit it to clear the retaining-rib *d* at the top of the frame A. It sometimes happens that the frame X, owing to a defect in the grip or other cause, has to be released from the supporting-frame on the car, and it will be noticed on referring to Fig. 8 that the frame X can, on removing the wedge M, be readily dropped from the frame A, the flat top of said frame X permitting the passage of the car over the dropped portion without interfering with the transverse bars B. As the handled wedge is detachable from the grip-frame, it offers no obstruction to the free manipulation of said frame in making any necessary repairs thereto.

The lever I, which is secured to the cam-shaft H, is of the form as best observed in Fig. 1, and is provided with a counterbalance-weight, P, which is adjustably secured to an arm, I', of the lever. A segmental bar, P', serves as a guide for the weight P, and prevents any lateral movement of the same in one direction, the frame A preventing such movement in the opposite direction. All twisting of the lever I and strain of the shaft H when the car runs at high speed round a curve is then prevented.

Q is the grip-operating rod, connected to any suitable operating mechanism on the car, this rod being connected to the lever I by a link, S, the pivot-points *s s'* at the opposite end of which are at right angles to each other, so as to permit the frame A to move laterally or vertically without straining the rod Q. A series of openings, *p*, in the lever I are arranged in the arc of a circle having its center at the axis of the shaft H, so that the point of connection of the link S to the lever may be shifted to compensate for wear of the parts and take up lost motion.

In the drawings the cam *h* is so placed on the shaft in respect to the lever I that any movement in the direction of the arrow, by pulling on the rod Q, will cause the cam to lift the bar F and close the grip-jaws, and when the rod Q is released the counterbalance-weight P will return the lever I to the position shown in Fig. 1, thereby permitting the bar F to fall and the grip-jaws to open. The cam may be so placed on the shaft in respect to the lever I that by elevating the lever the cam would depress the bar F, the construction of this portion of the operating

mechanism depending upon the character of the gripping devices used.

We claim as our invention—

1. The combination of the supporting-frame on the car, the grip-frame adapted thereto, and a retainer for said grip-frame, constructed to engage therewith as it is moved to release the grip-frame from the supporting-frame, whereby both grip-frame and retainer can be removed from the supporting-frame together, all substantially as specified. 75

2. The combination of the supporting-frame on the car, the grip-frame adapted thereto, and a grip-frame retainer constructed to engage therewith as it is moved to release the grip-frame from the supporting-frame, said retainer having a handle-bar, whereby it can be readily manipulated, all substantially as specified. 80

3. The combination of the supporting-frame on the car, the grip-frame adapted thereto, and a grip-frame retainer constructed to engage therewith as it is moved to release the grip-frame from the supporting-frame, said retainer being detachable from the grip-frame after the latter has been removed, all substantially as specified. 85

4. The combination of the grip-frame having a projecting bar, J, the retaining-wedge M, and the frame A, having shoulders for supporting said bar J, and keepers for the retaining-wedge M, all substantially as specified. 95

5. The combination of the grip-frame having a projecting bar, J, the frame A, having supporting-shoulders *c* and keepers *e*, and the retaining-wedge M, having lugs *n n* adapted to engage with the bar J as the wedge is removed from the keepers, all substantially as specified. 100

6. The combination of the supporting-frame A, the grip-frame, the sliding bar F, the shaft H, having a cam, *h*, acting on said bar, and a counterweighted lever, I, connected to the shaft and to the operating-rod, substantially as set forth. 105

7. The combination of the grip-operating shaft, the lever connected thereto, the operating-rod Q, and a link, S, connecting said rod to the lever and having joints at right angles to each other, all substantially as and for the purpose specified. 115

8. The combination of the grip-operating shaft H and its operating-arm I, having a counter-weight, P, with the carrying-frame having a bar, P', whereby said counter-weight is laterally guided, all substantially as specified. 120

In testimony whereof we have signed our names to this specification in the presence of two subscribing witnesses.
